(57) **CLAIM**

The ornamental design for a pant, as shown and described.

DESCRIPTION

FIG. 1 is a front elevational view of pants with the fly closed; FIG. 2 is a front elevational view of the pants of FIG. 1 with the fly folded open;

FIG. 3 is a rear elevational view of the pants of FIG. 1;

FIG. 4 is a top plan view of the pants of FIG. 1;

FIG. 5 is a bottom plan view of the pants of FIG. 1;

FIG. 6 is a side elevational view of the pants of FIG. 1, the other side being a mirror image;

FIG. 7 is a front elevation view of the pants with the fly closed, according to the second embodiment;

FIG. 8 is a front elevational view of the pants of FIG. 7 with the fly folded open;

FIG. 9 is a rear elevational view of the pants of FIG. 7;

FIG. 10 is a top plan view of the pants of FIG. 7;

FIG. 11 is a bottom plan view of the pants of FIG. 7;

FIG. 12 is a side elevational view of the pants of FIG. 7, the other side being a mirror image;

FIG. 13 is a front elevation view of the pants with the fly closed, according to the third embodiment;

FIG. 14 is a front elevational view of the pants of FIG. 13 with the fly folded open;

FIG. 15 is a rear elevational view of the pants of FIG. 13;

FIG. 16 is a top plan view of the pants of FIG. 13;

FIG. 17 is a bottom plan view of the pants of FIG. 13; and,

FIG. 18 is a side elevational view of the pants of FIG. 13, the other side being a mirror image.

The broken lines shown in the drawings are included for the purpose of illustrating environmental structure and form no part of the claimed design.

1 Claim, 12 Drawing Sheets
